UNITED STATES PATENT OFFICE

2,632,069

IMPACT OPERATED SWITCH

Mead Bradner, Foxboro, Mass., assignor, by
mesne assignments, to the United States of
America, as represented by the Secretary of the
Navy

Application January 16, 1950, Serial No. 138,740

8 Claims. (CL 200—52)

1

The present invention relates to electric switch actuating means and more particularly to electric switch actuating means whereby circuits may be operated when disposed in sealed or inaccessible locations.

When switch mechanisms are disposed in inaccessible locations such as within fluid tight bodies or the like, means must be provided for actuating the switch at the desired time. For example, in some types of naval torpedoes it is desired that the tubes comprising a part of the control mechanism be preheated prior to launching so that the control mechanism will be in condition to operate properly during and after the launching process. This is accomplished by means of a separate filament heater circuit which is kept separate from the main control circuit so that the energy of the batteries operating the latter will not be depleted. The above circuits are enclosed within the torpedo and hence normally are inaccessible. The present invention is particularly adapted for use in such installations since a simple hammer blow or the like on the side of the torpedo will suffice to actuate the control switch and energize the circuit.

Heretofore the operation of such circuits has involved the use of diaphragms, bellows, or other sealing means for shafts mounted in or extending through the exterior shell of the body. These arrangements complicate construction, jeopardize fluid tight integrity, and the exterior projections or releases required for such arrangements interfere with the overall streamlined contour of the torpedo.

It will of course be appreciated that the electric switch actuating means of the present invention need not be confined to operating circuits disposed in inaccessible locations but said means may be employed in any situation wherein circuit making or breaking operations must be performed.

An object of the present invention is to provide a novel means for actuating electric switches.

Another object is to provide means for actuating electric switches disposed in inaccessible locations.

Yet another object of the invention is to provide means for establishing a circuit disposed in an inaccessible location and having in combination therewith time delay means for interrupting the circuit.

Still another object of the invention is to provide a circuit maker and breaker which may be disposed on one side of a wall and be actuated by means of a blow applied to the other side of said wall.

2

A still further object of the invention is to provide a circuit controlling device for underwater ordnance which may be actuated prior to launching of the torpedo so as to make a circuit but which will automatically act to interrupt the circuit after a certain delay.

Other objects and their attendant advantages will become apparent as the following detailed description is read in conjunction with the accompanying drawing wherein:

Fig. 1 is a sectional side view partly in elevation of one embodiment of the present invention; and

Fig. 2 is a diagrammatic representation of a circuit employing electric switch actuating means of the present invention.

In the embodiment illustrated, the switch actuating means 19 comprises a hollow container 11 welded or otherwise rigidly secured so as to abut the inner surface of a wall 12 of a sealed body such as a naval torpedo. The bottom 13 of the container is suitably apertured at 14 to admit electrical leads 15 and 16 to the interior of the container. Floating within the container 11 on springs 17 and 18 is a large sleeve 19 which supports a shaft 20' upon which is mounted an inertia bar 20 having masses 21 and 22 of substantially equal weight on opposite ends thereof. The bar 20 is biased at one end by means of a retractile spring 23 so that the mass 21 normally abuts an anvil 24 integral with the top of the container 11 and contiguous with the shell 12 of the sealed body as shown. One end of the bar 20 bears an electric contact element 26 positioned to engage a mating contact element 27 secured on a bracket 27a whenever inertia bar 20 is actuated.

A circuit through contacts 26 and 27 is closed at the appropriate time by means of a light blow, as would be imparted by the small mallet 25 shown, on the sealed body directly over the anvil 24. The impact of this blow imparts sufficient kinetic energy through shell 12 and anvil 24 to the mass 21 to overcome the inertia of the bar 20 and cause it to rotate about point 29' in a counterclockwise direction.

If desired the circuit may thereafter instantaneously be broken by the retractile spring 23 which tends to return the parts to circuit open position. However, in the event that it may be desired to hold the circuit closed for a short period of time means may be employed for that purpose. For example, a circuit may be used in a naval torpedo as illustrated in Fig. 2 wherein is provided a relay 30 which when energized closes a switch 31 and thereby completes a filament circuit 36. Latch 32 serves to lock the switch 31 in "on" position and thereafter current

from battery 41 serves to heat parallel filaments 42, 43 and 44. Switch contacts 26 and 27 must remain engaged a sufficient length of time to assure proper operation of the relay 39 and locking engagement of latch 32 to retain the switch in its closed position. This may be assured by the provision of a time delay mechanism to cooperate with the inertia bar 20. Such a mechanism is illustrated in Fig. 1 and comprises a ratchet wheel 33 freely rotatable on shaft 20' and engageable by pawls 34 and 35 on the bar 20 when it is moved in a circuit breaking direction by the retractile spring 23. Rotatable with said ratchet is a spur gear 37 which meshes with a second spur gear 38 affixed to an escapement ratchet 39. An oscillating pawl 40 limits the speed of rotation of escapement ratchet in the usual manner and the period of oscillation of the pawl 40 determines the speed with which the switch contact elements 26 and 27 disengage after engaging. It will be apparent that the delay period may be varied by the provision of an oscillating pawl having different oscillating characteristics as is well known in the art, or the delay period may be changed by providing a train of any number of suitable gears between the oscillating pawl 40 and the ratchet 33 that will give the desired delay. Obviously, any movement delaying means such as a fan governor, inertia wheel or the like, may be substituted for the escapement ratchet and oscillating pawl.

In the operation of the circuit of Fig. 2 it will be apparent that the filament heater circuit may be established by a simple hammer blow at a selected spot on the outside of a torpedo. This circuit is established by the use of an electrically operated relay and suitable mechanical latching means is provided to retain the relay in actuated position after it is energized. Because of the time delay escapement arrangement the load applied to battery 45 is only of short duration and its power is therefore not depleted for its intended use elsewhere by means of connections A—A. It will be apparent, of course, that by varying the strength of the mallet blow it will be possible to vary the time interval with which the contacts 26 and 27 remain in engagement. A light blow, for example, will cause only a slight rotation of the bar 20 in order that only the end portions of the contacts engage so that the circuit thus will be interrupted after a correspondingly shorter period of time.

It should be understood, of course, that the foregoing disclosure relates to only a preferred embodiment of the invention and that numerous modifications or alterations may be made therein without departing from the spirit and scope of the invention as set forth in the appended claims.

What is claimed is:

1. Electric switch actuating means whereby a switch may be operated by an impact to first establish and after a delay interrupt the circuit comprising; an anvil portion accessible to receive an impact, an inertia member resiliently urged against the anvil portion and movable therefrom by a blow against the anvil, switch means for closing an electric circuit upon movement of said inertia member, retractile means for automatically opening said circuit, and time delay means to control the return movement of said inertia member whereby the circuit is interrupted after a predetermined time interval.

2. The claim as recited in claim 1 wherein said time delay means includes an escapement mechanism moved to set condition by movement of

said inertia member when the anvil receives a blow and thereafter releasable from set position by said retractile means acting upon said inertia member.

5. Electric switch actuating means whereby a switch may be operated by an impact to close a circuit and after a period of delay automatically interrupt the circuit comprising; an anvil portion positioned to receive an impact, a balanced inertia member pivoted about its center of gravity and having one end resiliently urged against the anvil portion and movable therefrom upon an impact blow against the anvil, switch means for closing an electric circuit upon movement of said balanced inertia member, retractile means for moving the switch means in a circuit breaking direction upon closing of the electric circuit, time delay means cooperating with said switch means whereby the circuit is interrupted after a period of delay, said time delay means comprising a ratchet movable when the switch means is moved in a circuit breaking direction, a gear train cooperating with said ratchet, and means connected with said gear train for delaying movement thereof whereby the opening of the switch means is delayed when it is moved in a circuit breaking direction by the retractile means.

4. An impact operated switch for closing an electric circuit comprising an anvil, a centrally pivoted arm, masses of equal weight at the opposite ends of the arm, one of the masses being normally urged against one side of the anvil so that a blow applied to the other side of the anvil will move therefrom the mass in contact therewith, an electric contact on the arm, and an electric contact spaced therefrom, the contacts being engaged to close the electric circuit upon movement of the arm by the impact of a blow imparted to the anvil.

5. An impact operated switch for closing an electric circuit comprising a housing, an anvil in one side of the housing, an inertia arm pivoted in the housing about its center of gravity and having one end normally urged against the inner side of the anvil, an electric contact on the arm, a mating electric contact spaced therefrom, the contacts being engaged to close the electric circuit upon movement of the arm by an impact on the outer side of the anvil.

6. An impact operated switch for closing an electric circuit in a sealed body comprising an impact receiving surface on the exterior of the body, a centrally pivoted arm within the body, masses of equal weight at the opposite ends of the arm, one of the masses being normally urged against the inner side of the body adjacent the impact receiving surface thereof, an electric contact on the arm, a fixed electric contact spaced therefrom, the contacts being engaged to close the electric circuit upon movement of the arm by impact of a blow imparted to the exterior impact receiving surface of the body.

7. An impact operated switch for closing an electric circuit comprising a housing, an anvil forming a part of the housing, a centrally pivoted arm within the housing, masses of equal weight at opposite ends of the arm, resilient means engaging both the housing and the arm for normally urging one of the masses against the anvil, an electric contact on the arm, a mating electric contact spaced therefrom, the contacts being engaged to close the electric circuit upon movement of the arm by impact of a blow imparting means to the anvil, said resilient means thereafter returning the arm toward its initial

position, and time delay means to control the return movement of the arm whereby the circuit is interrupted after a predetermined time interval.

8. An impact actuated switch for an electrical circuit comprising a housing, an anvil mounted on said housing, a centrally pivoted arm, masses of equal weight on opposite ends of the arm, a coil spring to urge one of the masses into engagement with one side of the anvil so that a blow applied on the opposite side of the anvil will cause the mass to move away from said anvil, an electric contact mounted on said arm adjacent said anvil contacting mass, a mating contact spaced therefrom and mounted on the housing, said contact being engaged to close the electrical circuit upon movement of the arm resulting from the impact of a blow struck on the anvil, said spring thereafter urging the arm toward its initial position, and a time delay means to control

the return movement of the arm whereby the circuit is interrupted after a predetermined time interval.
